VALVE MECHANISM FOR UNLOADING
COMPRESSORSCyril B. Fites, Ferguson, Mo., assignor to Wagner
Electric Corporation, St. Louis, Mo., a corpora-
tion of Delaware

Application October 25, 1939, Serial No. 301,102

4 Claims. (Cl. 230—30)

My invention relates to valve mechanism and more particularly to a valve mechanism for unloading a compressor when the pressure in receiver connected therewith reaches a predetermined value.

One of the objects of my invention is to produce an improved valve mechanism which will automatically shut off the intake of a compressor when the pressure in the receiver reaches a predetermined value and also vent the oil dome to atmosphere, which oil dome is associated with the compressor for lubricating purposes and has the oil therein subject to the discharged compressed fluid during the operation of the compressor.

Another and more specific object of my invention is to so construct the valve mechanism referred to that the venting of the oil dome will be controlled by the suction created by the compressor when the intake of the compressor is automatically closed by the predetermined pressure built up in the receiver.

Other objects of my invention will become apparent from the following description taken in connection with the accompanying drawings in which Figure 1 is a view, partly in section, of a compressor provided with an oil dome and showing my improved valve mechanism associated therewith, and Figure 2 is an enlarged sectional view showing details of the valve mechanism.

Referring to the drawings in detail, the rotary compressor is of known construction and comprises a stator 1 having eccentrically mounted therein a rotor 2 secured to a drive shaft 3 journaled in the end plates 4 and 5. The rotor 2 is provided with a plurality of spaced slots 6 extending in an axial direction in which are mounted reciprocable blades 7 (one only being shown) biased outwardly into engagement with the inner surface of the stator by springs 8. The end plate 4 is provided with an intake passage 9 and the end plate 5 with an outlet passage 10. Secured to end plate 5 is an oil reservoir or dome 11 which contains oil for the purpose of lubricating the compressor. In the construction shown the shaft 3 of the compressor drives an oil pump 12 to pump oil from the body of oil through passage 13 and discharge it into a well 14 through the opening 15. The oil in the well is free to flow through the passage 16 in shaft 3 and then into the compressor by way of the keyway 17 to thus provide lubrication for the movable parts of the compressor. In order that the oil may be forced into the compressor under

pressure during operation of the compressor, the body of oil in the oil dome is caused to be subject to the fluid under pressure discharged from the compressor. This is accomplished by having the discharge port 10 connected to a pipe 18 which extends above the oil line. An oil separator 19 removes any excess oil which may be discharged from the compressor together with the compressed air. The discharge port 10 has associated therewith a check valve 20 for preventing any of the compressed air from returning to the compressor. The oil dome communicates with the compressed air receiver or tank 21 by a conduit 22 and a check valve 23 prevents return of compressed air to the dome. The compressed air may be used for any purpose desired, as for example, the actuation of vehicle brakes.

In the type of compressor just described the compressor is generally automatically unloaded by shutting off the intake when the receiver for the compressed air discharged by the compressor reaches a predetermined value and again allowed to compress air when the compressed air in the receiver falls to a given pressure below the predetermined value. With such an arrangement it has been discovered that when the compressor is unloaded, an excess amount of oil may be fed to the compressor and cause it to become "choked" because of the compressed air acting upon the oil and forcing it into the compressor. It has also been discovered that the shutting off of the compressor by closing the intake does not cause the compressor to run idle since the compressor still operates to compress the air remaining in the compressor which may be partially discharged into the oil dome against the compressed air already therein or, if this is not accomplished due to insufficient air to compress, recirculated and recompressed continuously. The result of the compressor being partially under load and performing work is that it will continue to generate heat and use power notwithstanding no additional compressed air is being added to the receiver. All of these undesirable operating features present when the compressor intake is shut off can be eliminated to a large extent by also unloading the oil dome at the same time the intake is shut off. With the air in the oil dome under atmospheric pressure, the oil forced into the compressor will be reduced and the air and oil being circulated in the compressor will be free to be discharged into the oil dome against atmospheric pressure instead of against compressed air. A superior operating

compressor results which will require less power to operate when no air is required to be compressed. Also the compressor will operate at a much cooler temperature, less oil will be used, and the life of the compressor extended.

My improved valve mechanism 24, shown in detail in Figure 2, for shutting off the intake of the compressor and venting the oil dome to atmosphere is mounted on the compressor at the intake passage 9 by bolts 25. The valve mechanism comprises a casing 26 provided with a vertical bore 27 and a passage 28 for placing the intake passage in communication with the atmosphere through an air cleaner 29. The bore 27 adjacent the juncture of passage 28 has associated therewith a valve seat 30 for cooperation with a movable valve member 31 having an annular rib 32 for engagement with the valve seat. The valve member is formed with a slotted skirt 33 which projects into the bore and is guided thereby. A spring 34 positioned in bore 27 normally biases the valve member to open position against the threaded annular plug 35, this spring abutting a threaded adjusting member 36 whereby the tension of the spring may be adjusted as desired. The upper end of the valve member extends through the plug 35 and carries a piston 37 which has associated therewith a diaphragm 38. This diaphragm is sealed against the top of plug 35 by an annular ring 39 and spring 40 interposed between the ring and a closure plug 41 forming with the casing a chamber 42 above the diaphragm. This chamber communicates with a passage 43 in the casing and the passage is connected by a conduit 44 with the compressed air receiver or tank 21 whereby the diaphragm will be subject to the same fluid pressure as that in the tank.

The casing is also provided with a passage 45 which is connected to the interior of the top of the oil dome 11 by a conduit 46 and also communicates with the passage 28 in the valve casing by a short passage 47. A valve element 48 in the form of a plunger provided with a conical head 49 cooperates with the outlet end of passage 47 to control communication between the oil dome and passage 28 which, as previously stated, is in communication with the atmosphere through the air cleaner 29. The valve element 48 is mounted by a guide sleeve 50 on the casing and the outer end of the valve member has connected thereto a diaphragm 51 which is sealed to the casing by a cap 52, the latter forming with the diaphragm, a chamber 53. The conical end 49 of the valve member is normally held engaged with the end of passage 47 by means of a spring 54 interposed between the diaphragm and the cap 52. A passage 55 in the casing places the chamber 53 in constant communication with the bore 27 at a point between the valve member 31 and the intake passage 9 leading to the compressor.

When the compressor is operating, the parts of the valve mechanism are in the positions shown in Figure 2. Under these conditions air is free to pass through the air cleaner 29, passage 28, past the open valve member 31, and into the compressor where it is compressed and discharged into the top of the oil dome. Since the valve element 48 is biased to closed position, the oil dome will be sealed and the compressed air in the dome will pass into the air tank. In the valve mechanism shown, the spring 34 is adjusted so that the valve member 31 will remain open until a predetermined pressure of one hundred

pounds per square inch is effective in chamber 42 and also in the tank since this chamber is in constant communication with said tank. The spring 54 is of such strength that the valve member 48 will be held in closed position against the pressure in the oil dome.

With the compressor operating the pressure in the air tank and chamber 42 of the valve mechanism will ultimately be raised to one hundred pounds per square inch. When this occurs, the piston 37 will be forced downwardly, thereby moving the valve member 31 to closed position against seat 30. As the intake passage of the compressor is being cut off, a partial vacuum will begin to exist in the intake passage and the bore 27 which will cause the valve member to be pulled onto its seat at a rapid rate. When the valve member 31 is completely closed, the partial vacuum in bore 27 becomes quite high and since chamber 53 is in communication with the bore, the same partial vacuum will be present therein. This will cause the atmospheric pressure in passage 28 to move the diaphragm against the spring 54 and cause the valve element 48 to open passage 47 and place the dome in communication with the atmosphere through the air cleaner. With the air in the dome at atmospheric pressure the oil in well 14 will no longer be forced into the compressor under a pressure. Any air remaining in the compressor after the valve member 31 has become closed will be compressed and easily forced out into the oil dome through the outlet port check valve 20 which is no longer subject to a closing force by fluid under pressure. The compressor will now run idle since it is substantially completely unloaded. The power necessary to run the compressor will be a minimum and due to the fact that there will be no load imposed upon the blades, the temperature of the compressor and oil will drop substantially. Also, since the compressor is not doing any work under these conditions, it is not necessary to have a great amount of oil in the compressor. The oil that flows by force of gravity into the compressor is sufficient for lubrication and not so excessive as to "choke" up the compressor.

When the compressed air in tank 21 is used and the pressure therein drops to such a value that the spring 34 can move the valve member 31 off its seat against the action of the vacuum in bore 27 and the pressure on the diaphragm, the compressor will again begin to operate and compress air. With the opening of the intake the vacuum in bore 27 and chamber 53 becomes broken and permits the spring 54 to cause the valve element 48 to close passage 47 and again seal the oil dome. The compressor will now restore the maximum pressure in the air tank at which time the valve member 31 will be again closed and the dome connected to atmosphere in a manner already explained.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In combination with a compressor provided with an intake port and a discharge port and having associated therewith an oil reservoir communicating with the compressor for providing lubricant for the working parts of the

compressor and wherein the oil in the reservoir is subject to the discharged compressed fluid from the compressor prior to passage to a receiver, automatically operable means comprising a valve for closing the intake port when the fluid pressure in the receiver is a predetermined value, and means controlled by the suction created by the compressor when the intake port is closed for causing the oil reservoir to be vented to atmosphere.

- 5 2. In compressed air storage apparatus comprising a receiver and an air compressor provided with intake and discharge ports, an intake shut-off valve operative under condition of predetermined pressure in the receiver to close the intake port, a valve for placing the discharge port in communication with the atmosphere, and means for operating said last named valve, said means being made effective by suction produced by continued operation of the compressor after the intake port is closed.
- 10 3. In compressed air storage apparatus comprising a receiver and a rotary air compressor

provided with intake and discharge ports, an intake shut-off valve operative under condition of predetermined pressure in the receiver to close the intake port, a valve for placing the discharge port in communication with the atmosphere, and a vacuum motor for opening said valve, the vacuum chamber of said motor being constantly in communication with the intake passage of the compressor at a point between the compressor and said intake shut-off valve.

- 15 4. In compressed air storage apparatus comprising a receiver and an air compressor provided with intake and discharge ports, an intake shut-off valve operative under conditions of predetermined pressure in the receiver to close the intake port, a valve for placing the discharge port in communication with the atmosphere, said valve being resiliently biased to closed position, and means for opening said valve, said means being operated by subatmospheric pressure created by the compressor after the intake valve is closed.
